Primary Examiner — David Muller*Assistant Examiner* — Nathan Johnston(74) *Attorney, Agent, or Firm* — Leydig, Voit & Mayer(57) **CLAIM**

The ornamental design for an applicator device, as shown and described.

DESCRIPTION

FIG. 1 is a front elevation view of an applicator device of the present invention.

FIG. 2 is a rear elevation view thereof.

FIG. 3 is a top plan view thereof.

FIG. 4 is a bottom plan view thereof.

FIG. 5 is a right side elevation view thereof.

FIG. 6 is a left side elevation view thereof.

FIG. 7 is a perspective thereof.

FIG. 8 is a perspective view of the applicator device in a pressed down rotated configuration with the microneedle array descended; and,

FIG. 9 is a right side elevation view thereof.

The broken line showing of applicator device is included for the purpose of illustrating portions of the “article” and forms no part of the claimed design.

1 Claim, 9 Drawing Sheets(56)
